BY Frank D. Busser

ATTORNEY.

UNITED STATES PATENT OFFICE.

CHARLES J. MILLER, OF PHILADELPHIA, PENNSYLVANIA.

IRONING-PAD.

1,148,113.

Specification of Letters Patent. Patented July 27, 1915.

Application filed June 12, 1915. Serial No. 33,665.

To all whom it may concern:

Be it known that I, CHARLES J. MILLER, a citizen of the United States, residing at Philadelphia, county of Philadelphia, and State of Pennsylvania, have invented a new and useful Improvement in Ironing-Pads, of which the following is a full, clear, and exact description, reference being had to the accompanying drawings, which form a part 10 of this specification.

My invention relates to the padding which is placed over ironing boards and upon which the dampened articles to be ironed are placed. Such padding in its 15 most commonly used form consists of a number of thicknesses of a coarse cloth filler, into which all the moisture in the dampened articles is driven by the application of the hot iron. Such padding therefore soon becomes damp and soggy and its meshes 20 clogged up with starch, requiring frequent renewal. It has also been proposed to provide a resilient support or backing for the pad which will require only a reduced thickness of padding and through which the 25 moisture driven through the pad passes to the perforated bed plate or ironing board, but their expense of manufacture precludes their general use.

The objects of my invention are, to provide a resilient support or backing for the pad which will allow a more free passage for the moisture driven by the iron through the cloth padding and a more free circulation of air for carrying off the steam and vapor of said moisture, to permit a substantial reduction in the thickness of the padding, and at the same time to so simplify the construction as to reduce the cost of 35 manufacture to a point where it will be more economical, as well as more satisfactory, than the ordinary thick padding.

The invention is also of such a character as to readily adapt itself to the various 45 forms of laundry work; *i. e.*, a flat surface for shirt bosoms, a half round dome for cuffs, and a circular form for calendar rolls.

I will now describe the preferred embodiments of my invention depicted in the accompanying drawings, in which:

Figure 1 is a longitudinal section; Fig. 2 50 is an underneath view, of the flat form of my invention; Fig. 3 is a cross section through the same; Fig. 4 is a sectional view of the cuff-ironing form, and Fig. 5 is a cross section 55 therethrough.

To a sheet of woven wire mesh *a* is attached, on the under side, a series of parallel rods *b*, by means of thin metal clips *c* soldered to the wire mesh. The two outermost side rods *b'* are slightly thicker than the intermediate rods, thereby allowing for the buttons extending down the medial line of a shirt bosom. The resultant action of the pressure of the ironing plate *d* is approximately shown in the section, Fig. 3. The cloth padding *e* becomes very closely packed, and the line of buttons *f* tends to depress the medial line of the pad as shown. This is permitted not only by the difference 60 in size of rods *b* and *b'* but also by the 65 resilient qualities of the wire mesh.

The ironing board *g* is usually provided with perforations through which a blast of air is forced, for drying and ventilating 70 purposes. As may be readily seen, the wire mesh and the longitudinal rods permit complete ventilation and allow the moist vapors to escape as freely when the pad is in actual 75 use. Besides, the wire mesh affords an ideal 80 drainage for the cloth padding.

As shown in Fig. 1, the backing pad is slightly bowed and after the pressure of the iron is removed the backing reassumes 85 this arched form and aids materially in free ventilation.

As shown in Fig. 4, the backing pad *h* for cuff ironing is given a similarly bowed form by being bent at a more acute angle than the ironing board so that normally 90 only its ends rest upon the ironing board *i*. The descent of the cuff iron *j* presses the pad down onto the ironing board, when drainage and ventilation take place as in the case of the shirt bosom form.

As seen in Fig. 5 the rods *k* underneath the cuff-pad backing are all the same size, and they act, as in the previous case, to support the wire mesh from direct contact with the ironing board, allowing free circulation 100 of air thereunder, and also add the necessary spring and resilience.

The metal backing plate and rods are preferably made of brass or coated with a preparation to prevent rusting.

Having now fully described my invention, what I claim and desire to protect by Letters Patent is:

1. An ironing pad for laundry pressing machines comprising a flexible perforated 110 backing plate and resilient rods secured to the under side thereof.

2. An ironing pad for laundry pressing machines comprising a flexible perforated backing plate and rods arranged in parallel relation and spaced and secured to the under side thereof, the outermost rods being thicker than the intermediate rods.
3. An ironing pad for laundry pressing machines comprising a flexible perforated backing plate and resilient rods spaced apart and secured to the underside thereof, the structure being bent or bowed in the direction of the length of the rods.
4. An ironing pad for laundry pressing machines comprising a wire mesh backing plate and rods arranged in parallel relation and spaced apart and secured to the under

side thereof, the structure being bent or bowed in the direction of the length of the rods.

5. An ironing pad for laundry pressing machines comprising an ironing board, a wire mesh backing plate, and rods spaced apart and arranged in parallel relation and secured to the under side of the plate, the structure being shaped to normally contact with the ironing board only at opposite end portions of the rods.

In testimony of which invention, I have hereunto set my hand, at Philadelphia, on this 11th day of June, 1915.

CHARLES J. MILLER.
